United States Patent Office.

CYRUS HILL, OF DOVER, MAINE.

Letters Patent No. 61,427, dated January 22, 1867.

IMPROVED COMPOSITION FOR ROOFING.

The Schedule referred to in these Letters Patent and making part of the same.

TO ALL WHOM IT MAY CONCERN:

Be it known that I, CYRUS HILL, of Dover, county of Piscataquis, and State of Maine, have invented a new and useful Composition for Making Roofs, Covering Walls, Pavements, &c.; and I do hereby declare that the following is a clear, full, and exact description of the same.

To enable others to compound and use my invention, I will proceed to describe it.

I take of coal tar three gallons; linseed oil one quart; of clay, plaster, and pulverized slate, each an equal quantity, and mix into the tar and oil until it forms a paste of proper consistency to spread easily. When thus prepared, this compound forms an elastic cement, that is water-proof and not liable to crack by exposure to the extremes of heat and cold. It is spread on tarred paper or canvas in the usual manner for forming a roof. It is also well adapted for covering the walls of cisterns, cellars, &c., and also for forming pavements or walks.

Having thus described my invention, what I claim, is—

The composition for covering roofs and for similar purposes, consisting of the ingredients herein named, and united in the proportions substantially as set forth.

CYRUS HILL.
